William Casey, INVENTOR.

BY *O. V. Thiele*

ATTORNEY.

UNITED STATES PATENT OFFICE.

WILLIAM CASEY, OF KINGSTON, ONTARIO, CANADA.

LOCOMOTIVE STOP VALVE.

Application filed July 21, 1927. Serial No. 207,366.

In modern locomotive practice, the arrangement is rapidly coming into favor by which the throttle means controlling the flow of steam to the steam chests of the engines are located at a point between the superheater and the steam chests. This makes available at all times a supply of superheated steam for the operation of auxiliaries, and has certain other advantages such as prompter starting and stopping of the locomotive, smaller likelihood of slipping the wheels, etc. Under some conditions it may be required, however, to have means to shut off the steam inlet to the superheater. It is the object of the present invention to supply improved means of this sort.

The invention is illustrated in the single sheet of drawings herewith in which Fig. 1 shows in longitudinal central section such portions of a locomotive with my invention applied as are necessary to make the invention clear; Fig. 2 shows a section on an enlarged scale on line 2—2 of Fig. 1; and Fig. 3 shows a section on line 3—3 of Fig. 2.

The barrel 1 of the locomotive is equipped with the steam dome 2 into which extends the dry pipe 3 which conveys the steam to the superheater header 4. The particular construction of the superheater is of no interest in the present connection, and is, therefore, not indicated in the drawings. It is understood by all those conversant with this art that the steam is returned to the superheater header 4 in a superheated state, and from it is conducted through the connections 5 (only one appearing in the drawing) to the steam chests of the locomotive. The steam flow to the connections 5 is controlled in the form of the drawings by a series of small valves 6 (only one of which shows in the drawings, the others lying in line directly behind it). These valves are operated from the cab by means of a rod 7, arm 8 and shaft 9.

This arrangement, as mentioned above, is a typical one, and is used here only for illustrative purposes. What is essential is that the steam is controlled by some form of throttling means between the outlet from the superheater and the engines. The shutoff valve can be applied anywhere in the dry pipe between its inlet and the superheater. In the form of shutoff valve herein disclosed, the valve is placed so it shuts off the steam at the very inlet to the dry pipe. The valve consists of a flat disk 10 and a carrier member 22 and means for lowering it into the position so it

seats on the end of the dry pipe and for raising it up and out of the way for normal running of the locomotive.

The sheet 11 constituting the cover for opening 12 of the steam dome is provided with a threaded hole 13 aligned centrally with the inlet of the dry pipe. Into this threaded hole is screwed the plug 14 through whose axial opening 15 extends the stem or rod 16. The plug is preferably welded at 14^a to make it steam tight. The lower end of the opening 15 flares out into a conical seat 17 against which may be seated the upper surface 18 of the collar 19. The surface 18 is preferably given the shape of a spherical segment so that the seat between 18 and 17 is substantially a circular line. The upper end of the stem 16 is threaded, the threads being engaged by the corresponding threads of the castellated nut 20. This nut when once in proper position is locked by means of the key 21 in the usual manner.

The part of the stem 16 below the collar 19 is threaded and engages the carrier 22, this carrier being internally threaded to engage the threads on the stem. The carrier has an integral collar 23, the lower side of which is in the shape of a spherical segment adapted to engage a seat surrounding the upper side of an opening 24 through the disc 10. The seat in the disc is preferably made conical in shape so that here also there is line contact between the two seats. The upper side of the collar 23 is adapted to engage the cover 29 which is secured by means of the stud bolts 25 to the disc 10. The upper portion of the carrier and the opening in cover 29 through which it extends are square in cross-section. The lower end of the stem 16 extends into the closed cavity 26 in the carrier 22. Studs 27—27 screwed into the cover 11 and ears 28—28 integral with the disc 10 prevent the valve from turning.

The operation of this device will readily be understood. When the valve is open as it is during normal operation of the locomotive, the nut 20 is pulled up so as to cause the two seats 18 and 17 to engage. This prevents all leakage between the stem 16 and the plug 14. The plug being welded in as at 14^a prevents any leakage between the plug and the cover 11.

When the valve is to be closed key 21 is removed and nut 20 is loosened sufficiently so that stem 16 can be turned. In the form illustrated this is done with a wrench applied

to the squared upper portion 16^a of the stem 16, although obviously means permanently in place may be provided for this purpose, such as a wheel. Turning stem 16 in the proper direction lowers the valve, the studs 27 preventing its turning during this motion. The disc 10 at this time is suspended on the collar 23 by means of the cover 29. When the valve has been lowered sufficiently, it engages the upper edge of the dry pipe which for this purpose is ground to a proper seat as above described.

The loosening of nut 20 has broken the tight bearing between seats 18 and 17. By further turning the stem 16 after the valve has become seated on the open end of the dry pipe, carrier 22 and cover 29 become disengaged, the former descending and its lower surface engaging the seat surrounding the opening 24. A further forcing of the stem 16 forces these two seats together, and at the same time again seats 18 against the seat 17. Leakage between stem 16 and plug 14 and past carrier 22 and disc 10 is thus effectually prevented. It will be obvious that some variations can be introduced into the invention as illustrated in the drawing, and described in the above specification, without departing from the spirit of the following claims.

30 I claim:

1. In a locomotive, the combination of a steam dome comprising a dome sheet, a dry-pipe extending into the dome and having its end shaped to form a valve seat, a disc-shaped valve adapted to engage said seat, a plug in the dome sheet, a rod extending through the plug and having screw means adapted to operate the valve, a collar on said rod adapted to engage the plug to make a steam-tight joint, said screw means adapted to force said collar against said plug when the valve is closed, and other screw means to force said collar against the plug when the valve is open.

45 2. In a locomotive, the combination of a steam dome comprising a dome sheet, a dry-pipe extending into the steam dome and having its end shaped to form a valve seat, a disc-shaped valve adapted to engage said seat, a plug in the dome sheet, a rod extending through the plug and adapted to operate the valve, a collar on said rod adapted to seat

against the inner end of the plug to form a steam-tight joint, said rod having a screw thread on its outer end, and a nut on said end, whereby the collar can be pulled up against the plug to make a tight joint and loosened to permit the rod to operate the valve.

5 3. The combination according to claim 2, the rod having another thread to force the valve to its seat and simultaneously to force the collar against the plug.

4. The combination according to claim 2, the valve comprising a screw threaded element adapted to abut against the outer side of the main body portion of the valve, the rod being threaded to engage the thread of said element, whereby a turning movement of the rod in the proper direction will force the collar against the plug and the element against said main body portion of the valve and the valve against its seat.

5. In a locomotive, the combination of a steam dome comprising a dome sheet, a dry-pipe extending into the steam dome and having its end shaped to form a valve seat, a disc-shaped valve adapted to engage said seat, a plug in the dome sheet, a rod extending through the plug and adapted to operate the valve, a collar on said rod adapted to seat against the inner end of the plug to form a steam-tight joint, said rod having a screw thread on its outer end, a nut on said end, the main body portion of said valve having a perforation aligned with said rod, the outer end of the perforation having a seat, a screw-threaded element forming a part of the valve and having a corresponding seat to engage the seat at the perforation, a second element secured to said main body portion of the valve and adapted to be engaged by the first element to lift the valve, said rod having a threaded portion to engage the screw-threaded element, and means to keep the valve from rotating, whereby when the valve is open the collar may be pulled against the plug by means of the nut, and when the valve is closed the collar may be forced against the plug and the first-named element against the seat at the perforation and the valve against its seat by means of a rotation of the rod.

WILLIAM CASEY.
